UNITED STATES PATENT OFFICE.

HUGH MUNROE HUNTER, OF CLEVELAND, OHIO, ASSIGNOR TO THE NATIONAL-ACME MANUFACTURING COMPANY, OF CLEVELAND, OHIO, A CORPORATION OF OHIO.

METAL-WORKING MACHINE.

1,081,964.

Specification of Letters Patent.

Patented Dec. 23, 1913.

Application filed February 26, 1912. Serial No. 679,811.

To all whom it may concern:

Be it known that I, HUGH M. HUNTER, a citizen of the United States, residing at Cleveland, in the county of Cuyahoga and State of Ohio, have invented certain new and useful Improvements in Metal-Working Machines, of which the following is a specification.

This invention relates to metal working machines, and more particularly to that class thereof known as multiple spindle machines, the object of the invention being to provide a multiple spindle machine having improved work forming means by means of which when angular stock is being formed the chattering and vibration of the tool will be largely overcome as well as the extreme resistance to the working of the tool avoided, and by means of which improvement an increased production of from thirty to fifty per cent. is obtained whether the stock be round or angular.

In the drawings accompanying and forming part of this specification, Figure 1 is a perspective side view of a portion of a multiple spindle machine having this improved forming mechanism; Fig. 2 is a perspective side view of the opposite side of the machine illustrating more clearly the different forming operations on the same piece of work; Fig. 3 is a perspective side view of the same side of the machine as that shown in Fig. 1, but illustrating one of the forming tool carriers thrown upward and out of its working position; Fig. 4 is an end view of the turret end of the machine looking from right to left in Fig. 1; Fig. 5 is a diagrammatic view illustrating the movement of one of the forming tools during its operation; Fig. 6 is a detail perspective view of the tool carrier shaft; and Figs. 7, 8, 9 and 10 are views illustrating respectively the first, second and third forming operations and the cutting off operation.

Similar characters of reference indicate corresponding parts throughout the figures of the drawings.

In machines of this general class, where the forming tool makes a wide cut on a hexagon or square bar there has always been considerable chattering and vibration, and therefore more or less trouble on account of the extreme resistance to the forming tool while passing over the corners of the stock. In other words, during the rotation of the stock,

every time the tool comes into contact with the corner of the angular formed stock it meets with the heaviest resistance. Furthermore, when the tool starts into the work it strikes the corner first, as this is the greatest diameter of the stock. Consequently, as the tool in starting into the work first engages that part of the stock having the greatest diameter, and therefore one of the corners of the stock, it does not do any further work until it strikes the next corner during the rotation of the stock, and this causes the tool to chatter, as in effect the piece of work is rotating irregularly. By means of the present improvement this chattering is largely eliminated, as I am able to perform the first two forming operations by a shearing cut. In other words, by using a single forming tool it is impracticable to make a shearing cut on the stock, for the reason that the piece of work would be left in that shape after the tool finished cutting, but in the present improvement, by having three forming tools a shearing cut can be made in one direction by the first tool, a shearing cut in an opposite direction by the second forming tool, and the third tool forms the work into the cylindrical shape in which it is desired, in which form it is usually necessary to leave the stock, and the cuts in each case will be smaller, so that such cuts can be made faster and the tendency to chatter practically eliminated by reason of this shearing cut over the corners or angles of the work. Furthermore, whether the forming operations take place upon angular formed stock or cylindrical stock the output of the product is materially increased by performing these forming operations in three steps, since by having three different positions in which to carry on the forming operations the time within which they are performed is reduced from thirty to fifty per cent. In other words, although the forming work is performed in three operations in the present improvement, all of these operations are done in the time that would be necessary to properly cut the work with a single tool. In other words, by dividing up the operations the time that it takes for the tool to make the longest operation on the piece is divided so that the actual time of making that piece is reduced just that much. In other words, heretofore where the forming operation had to be performed with a flat

60

110

5 tool, and therefore had to go into the work slowly, especially where angular pieces were being cut, if it took a minute to make a forming cut with one such tool by dividing this forming operation into three, using three forming tools, the forming work can be done in one-third the time. If heretofore the forming operation was performed with two forming tools, by using three the time of doing that work is cut in half, since all of 10 the tools are operating simultaneously and at each operation of the three tools a piece of work is being completely formed. Furthermore, it is necessary that a forming tool, to 15 form accurately and properly, should cut on the center, and the present improved mechanism provides a machine in which this result is practically obtained.

20 In the present embodiment of this improvement, it comprises a rotatable turret 2 carried by the casing 3, which turret is provided with a series of work spindles 4, shown herein as four in number, the turret and spindles being respectively indexed and 25 rotated by some suitable means not necessary to be described herein. The base 5 upon which the turret is mounted also supports a sliding tool carrier 6 shiftable by suitable means toward and from the turret. 30 At each side of the turret is mounted a compound slide 7 adjustable toward and from the turret in the manner usually provided for this purpose, and a part of which is shiftable toward and from the axis of the 35 turret by levers 8 operated by suitable cams carried by a cam-drum on the cam shaft, not necessary to be shown herein. In the present instance the compound slide at the left of the machine carries a forming tool 40 9 so formed that it will make a shearing cut, while the compound slide at the right of the machine carries a cutting off tool 10 for cutting off the work after the forming operations are completed.

45 Connected with each of the compound slides in the manner hereinafter described is a swinging forming tool carrier 11, and as each is a duplicate of the other a description of one thereof is deemed sufficient. 50 Mounted on the turret casing is a bracket 12 having a pair of sleeves or bearings 13 and 14 for the reception of short eccentrically formed shafts 15; that is to say, each shaft is rotatably supported in its bearing 55 sleeve, being held therein against longitudinal play and is provided with a short portion 16 eccentrically located to that part 17 thereof which projects into the bearing sleeve. Loosely mounted upon adjustable 60 cone bearings carried by the eccentric portion of each of these shafts is a depending forming tool carrier 11 constructed to receive a forming tool 18, and for this purpose the carrier is shown provided at its 65 upper end with a sleeve 19 mounted on the

eccentric portion 16 of the shaft, depending from which sleeve is an arm 20 carrying a U-shaped portion 21 for the reception of the forming tool holder 22, which may be adjusted therein in any desired way. The 70 part 17 of the eccentric shaft is provided with a projecting lug 23 shown bifurcated and forming a crank carrying the upper end of a pivotally located link 24, the lower end of which in turn is pivotally connected to 75 one arm 25 of what may be considered a bell-crank lever 26, the hub of which is pivotally secured, as at 27, to a projection 28 of the bracket carrying the eccentric shaft. The lower end of the other arm 29 of this bell-crank lever is bifurcated, as at 80 30, or it may be slotted for the reception of a pin 31 carried by the forming tool carrier, the construction of the bifurcated end being such that this bell-crank lever can move back and forward on the pin of the carrier. When the lower end of the bell-crank lever or link is bifurcated it enables the forming tool carrier—on separating such link from its pin 31 and detaching one end of the 85 turnbuckle hereinafter described—to be thrown upward as shown in Fig. 3 much more easily than if the lower end is provided with a slot. By so constructing the 90 machine that these carriers may be thrown upward the insertion of the forming tools in the carrier and in the compound slide is very much facilitated as well as affording accessibility to the mechanism adjacent to the work spindles. Each of the tool carriers 95 is connected to the compound slide by means of a turnbuckle 35 having a right and left hand thread provided with a knurled center-piece. This turnbuckle enables the 100 depth of the forming cuts to be regulated. The inner end of the turnbuckle is connected to a projection on the carrier, which is provided with a series of holes whereby the angular position of the turnbuckle may 105 be changed if desired. Each of the carriers 110 is provided with a handle socket 37 for the reception of a handle 38 by means of which, in the manner hereinbefore described, it may be swung away from the work. By this construction it will be observed that as the 115 lower forming and cutting off tool slides are moved toward and from the work the swinging tool carriers are also swung toward and from the work and at the same time, owing to the eccentric shafts which 120 support them the tool carriers are raised and lowered, but by reason of the fact that each tool carrier is linked in the manner hereinbefore described to the crank carried by the eccentric shaft the tool is caused to 125 move in such manner as to cut on the center of the work; that is to say, it will cut in a straight line from the circumference of the piece of work toward the center for the 130 distance which the tool is to cut. In other

words, by reason of the fact that the forming operations are divided into three the tool does not have to penetrate the work more than about one-quarter of the diameter thereof. Consequently, by supporting the carrier in the manner shown herein it will during its cutting operation cut on the center.

From the foregoing it will be observed that by constructing two of the forming tools so that each will make a shearing cut the first forming cut will be made by that tool carried by the compound slide shown at the left of the turret in Fig. 4 so as to cut the work in the manner shown in Fig. 7. When this cut has been completed the turret is rotated or indexed in the usual manner and the piece of work is rotated into position to be operated upon by the forming tool carried by the swinging carrier 11 at the left of the turret, simultaneously with which, of course, the forming tool immediately below it is performing its work on a new piece of stock. The forming tool carried by the swinging carrier at the left of the machine then makes a shearing cut similar to that shown at the left of Fig. 8, after which the turret is again rotated or indexed to carry this truncated piece of work into position to be operated upon by the other swinging forming tool at the right of the turret, at which time, of course, the two previous forming tools are cutting on different pieces of stock. For a large amount of work the stock, of course, could not be left in the condition shown in Fig. 8, and therefore the right hand swinging forming tool at this time cuts the work so as to leave it in the shape shown in Fig. 9, subsequent to which, on the next indexing of the turret, the piece may be cut off by the cutting off tool carried by the right hand compound tool slide in the manner shown in Fig. 10, by which time the operations of the tools of the sliding tool carrier on the work are also completed. Of course, when round stock is being operated upon it is not necessary that the forming tools make a shearing cut, but by the present improvement the stock may be completely formed in much less time, as hereinbefore pointed out, whatever the form of the stock may be, and when angular formed pieces are being worked it is practicable in the present improvement to make shearing cuts, which thus very materially eliminate chattering and vibration of the tools. From the foregoing it will thus be observed that in the present improvement the time required to finish one piece of work, so far as the forming operations are concerned, is equal only to the time required for one single operation, and as each single forming operation is necessarily much shorter than that heretofore necessary where one tool is used it follows that the output of the ma-

chine is very materially increased while chattering and vibration of the tools is practically eliminated by reason of the fact that shearing cuts may be made, while at the same time the forming tools may all cut on the center. 70

In the present embodiment the bracket 12 is connected with the base of the machine by means of a suitable stay rod 40, which is useful for steadyng the swinging forming tool carrier bracket, it being necessary, however, to use only one of these stay rods, and this at that side of the machine where the heaviest forming operations take place. 75

In practice the sleeves 13 and 14 of the bracket or housing 12 will be provided with adjustable cone bearings substantially similar to those shown in dotted lines in Fig. 1 at the forward end of the shaft 15 for supporting the carrier 11 for taking up all play 80 or wear of the parts. 85

In the diagrammatic view, Fig. 5, illustrating the movement of the forming tool, the perpendicular dotted lines *b* illustrate the swinging movement of the carrier 11, 90 while the horizontal dotted line *c* illustrates the movement of the cutting tool cutting on the center, and the curved dotted line *a* illustrates the movement the cutting tool would take if there was no rising and falling movement of the swinging carrier. The dotted lines *e* show the rising and falling or oscillatory movement of the crank arm 23 of the eccentric shaft. 95

I claim as my invention:

1. In a multiple spindle machine, the combination of a rotatably supported turret carrying a plurality of spindles for the work, a plurality of side tool supports located at the same side of the machine, means for pivotally supporting one of said supports, said pivot being eccentrically journaled, means for swinging said pivoted tool support and for turning said pivot in its eccentric bearing whereby the tool will move approximately in a straight line, and means for simultaneously operating the other tool support whereby the tools may operate simultaneously upon the work and successively upon the same piece of work. 100 105 110 115

2. In a multiple spindle machine, the combination of a rotatably supported turret carrying a plurality of spindles for the work, a plurality of side tool supports, means for pivotally supporting one of said supports, said pivot being eccentrically journaled, means for swinging said pivoted tool support and for turning said pivot in its eccentric bearing whereby the tool will move approximately in a straight line, and means for operating the other tool support whereby the tools carried thereby will act successively upon the work. 120 125

3. In a multiple spindle machine, the combination of a rotatably supported turret car- 130

2. 1. In a multiple spindle machine, the combination of a rotatably supported turret carrying a plurality of spindles for the work, a plurality of side tool supports supported independently of each other, one for sliding movement, means for pivotally supporting the other support above said sliding side tool support, said pivot being eccentrically journaled, means for swinging said pivoted tool support and for turning said pivot in its eccentric bearing whereby the tool will move approximately in a straight line, and means for operating said sliding tool support in unison with said swinging tool support whereby the tools carried thereby may operate simultaneously upon the work and successively upon the same piece of work.
10. 2. In a multiple spindle machine, the combination of a rotatably supported turret carrying a plurality of spindles for the work, a plurality of side tool supports supported independently of each other but connected together, one supported for sliding movement, means for pivotally supporting the other support above said sliding side tool support, said pivot being eccentrically journaled, means for swinging said pivoted tool support and for turning said pivot in its eccentric bearing whereby the tool will move approximately in a straight line, and means for operating said sliding tool support in unison with said swinging tool support whereby the tools carried thereby may operate simultaneously upon the work and successively upon the same piece of work.
20. 3. In a multiple spindle machine, the combination of a rotatably supported turret carrying a plurality of spindles for the work, a plurality of side tool supports, and means for actuating all of said supports whereby the tools carried thereby may simultaneously operate upon the work and successively upon the same piece of work.
25. 4. In a multiple spindle machine, the combination of a rotatably supported turret carrying a plurality of spindles for the work, a plurality of side tool supports supported independently of each other but connected together, one supported for sliding movement, means for pivotally supporting the other support above said sliding side tool support, said pivot being eccentrically journaled, means for swinging said pivoted tool support and for turning said pivot in its eccentric bearing whereby the tool will move approximately in a straight line, and means for operating said sliding tool support in unison with said swinging tool support whereby the tools carried thereby may operate simultaneously upon the work and successively upon the same piece of work.
30. 5. In a multiple spindle machine, the combination of a rotatably supported turret carrying a plurality of spindles for the work, a plurality of side tool supports, and means for actuating all of said supports whereby the tools carried thereby may simultaneously operate upon the work and successively upon the same piece of work.
35. 6. In a multiple spindle machine, the combination of a rotatably supported turret carrying a plurality of spindles for the work, a plurality of side tool supports supported independently of each other, and means for actuating them in unison whereby the tools carried thereby may simultaneously operate upon the work and successively upon the same piece of work, each of said side tool supports carrying a tool, said tools having their cutting edges located differently relatively to each other and to the line of movement, whereby one tool will make a cut different from that of the preceding tool.
40. 7. In a multiple spindle machine, the combination of a rotatably supported turret car-

rying a plurality of spindles for the work, a series of three forming tool supports carrying tools operative simultaneously upon the work and successively upon the same piece of work and each effective to perform a third of the forming operation upon the work whereby the complete forming of a piece of work takes place during the forming operation of each tool, and means for operating said tools.

8. In a multiple spindle machine, the combination of a rotatably supported turret carrying a plurality of spindles for the work, a series of forming tool supports carrying tools and comprising a pair of sliding tool supports and a pair of swinging tool supports, means for eccentrically supporting each of said swinging supports, and means for actuating said sliding tool supports and said eccentric supporting means, whereby the tools carried thereby may simultaneously operate upon the work and successively upon the same piece of work.

9. In a multiple spindle machine, the combination of a rotatably supported turret carrying a plurality of spindles for the work, a series of forming tool supports carrying tools and comprising a pair of sliding tool supports and a pair of eccentrically supported swinging tool supports, and means for actuating all of said supports in unison whereby the tools carried thereby may simultaneously operate upon the work and successively upon the same piece of work, each of said tool supports being independently supported a pair thereof at each side of the work and each pair connected together for movement in unison.

10. In a multiple spindle machine, the combination of a rotatably supported turret carrying a plurality of spindles for the work, a side tool support movable toward and from the work, a swinging side tool support located above said side tool support and movable therewith toward and from the work so that the tools carried by said tool supports may simultaneously operate upon the work and successively upon the same piece of work, means for eccentrically supporting said swinging side tool support, and means for actuating said means.

11. In a multiple spindle machine, the combination of a rotatably supported turret carrying a plurality of spindles for the work, a swinging side tool support movable toward and from the work, means for swinging said side tool support, and means for raising and lowering said side tool support during its swinging movement.

12. In a multiple spindle machine, the combination of a rotatably supported turret carrying a plurality of spindles for the work, a sliding side tool support movable toward and from the work, a swinging side tool support located above and connected

with said side tool support and movable therewith toward and from the work so that the tools carried by said tool supports may simultaneously operate upon the work and 5 successively upon the same piece of work, and means for swinging and for raising and lowering said swinging side tool support during its swinging movement.

13. In a multiple spindle machine, the 10 combination of a rotatably supported turret carrying a plurality of spindles for the work, a sliding side tool support movable toward and from the work, a swinging side tool support connected with said side tool 15 support and movable therewith toward and from the work so that the tools carried by said tool supports may simultaneously operate upon the work and successively upon the same piece of work, and means for giving 20 the swinging side tool support a rising and falling movement during its swinging movement.

14. In a multiple spindle machine, the 25 combination of a rotatably supported turret carrying a plurality of spindles for the work, a pair of opposed side tool supports movable toward and from the work, a pair of swinging side tool supports located above said opposed side tool supports and connected 30 and movable therewith toward and from the work so that the tools carried by said tool supports may simultaneously operate upon the work and successively upon the same piece of work, means for swinging said 35 swinging side tool supports, and means for raising and lowering them during their swinging movement.

15. In a multiple spindle machine, the 40 combination of a rotatably supported turret carrying a plurality of spindles for the work, a pair of opposed sliding side tool supports movable toward and from the work, and a pair of eccentrically supported and swinging side tool supports located above said opposed 45 side tool supports and connected and movable therewith toward and from the work so that the tools carried by said tool supports may simultaneously operate upon the work and successively upon the same piece of 50 work.

16. In a multiple spindle machine, the 55 combination of a rotatably supported turret carrying a plurality of spindles for the work, a pair of opposed sliding side tool supports movable toward and from the work, a fixed bracket carrying a pair of eccentrically formed shafts, a swinging side tool support carried by each of said shafts, a linkage connection between each of said 60 shafts and each of said swinging side tool supports, said linkage connection being also pivotally supported by a fixed part of the machine, and means connecting each swinging side tool support with a sliding side tool support whereby they will move in 65

unison so that the tools carried thereby may simultaneously operate upon the work and successively upon the same piece of work.

17. In a multiple spindle machine, the 70 combination of a rotatably supported turret carrying a plurality of spindles for the work, a pair of opposed sliding side tool supports movable toward and from the work, a fixed bracket carrying a pair of eccentrically formed shafts, a swinging side tool support carried by each of said shafts, a linkage connection between each of said shafts and each of said swinging side tool supports, said linkage connection being also pivotally supported by a fixed part of the 75 machine, and means adjustably connecting each swinging side tool support with a sliding side tool support whereby they will move in unison so that the tools carried thereby may simultaneously operate upon the work 80 and successively upon the same piece of work.

18. In a multiple spindle machine, the 85 combination of a rotatably supported turret carrying a plurality of spindles for the work, a pair of opposed sliding side tool supports movable toward and from the work, a fixed bracket carrying a pair of eccentrically formed shafts, a swinging side tool support carried by each of said shafts, a linkage connection between each of said shafts and each of said swinging side tool supports, said linkage connection being also pivotally supported by a fixed part of the 90 machine, and means adjustably and detachably connecting each swinging side tool support with a sliding side tool support whereby they will move in unison so that the tools carried thereby may simultaneously operate upon the work 95 and successively upon the same piece of work.

19. In a multiple spindle machine, the 100 combination of a rotatably supported turret carrying a plurality of spindles for the work, a sliding side tool support movable toward and from the work, a fixed bracket, an eccentrically formed shaft carried by the bracket, a swinging side tool support suspended from said shaft, a linkage connection between said shaft and the swinging 105 side tool support and also having a fixed pivotal connection, and means connecting said swinging side tool support with the sliding tool support whereby they will move in unison to permit the tools carried thereby to simultaneously operate upon the work and successively upon the same piece of work.

20. In a multiple spindle machine, the 110 combination of a rotatably supported turret carrying a plurality of spindles for the work, a sliding side tool support movable toward and from the work, a fixed bracket, an eccentrically formed shaft carried by the bracket, a swinging side tool support sus- 115

120

125

130

pended from said shaft, a linkage connection between said shaft and the swinging side tool support and also having a fixed pivotal connection, and adjustable means connecting said swinging side tool support with the sliding tool support whereby they will move in unison to permit the tools carried thereby to simultaneously operate upon the work, and successively upon the same piece of work.

21. In a multiple spindle machine, the combination of a rotatably supported turret carrying a plurality of spindles for the work, a sliding side tool support movable toward and from the work, a fixed bracket, an eccentrically formed shaft carried by the bracket, a swinging side tool support suspended from said shaft, a linkage connection between said shaft and the swinging side tool support and also having a fixed pivotal connection, and adjustable and detachable means connecting said swinging side tool support with the sliding tool support whereby they will move in unison to permit the tools carried thereby to simultaneously operate upon the work, and successively upon the same piece of work and whereby also the swinging side tool support may be thrown away from the work to permit access thereto.

22. In a multiple spindle machine, the combination of a rotatably supported turret carrying a plurality of spindles for the work, a sliding tool support movable toward and from the work, a fixed bracket, an eccentrically formed shaft rotatably carried thereby, a swinging side tool support loosely mounted on said shaft, a crank arm secured to said shaft, linkage connection between said crank arm and said swinging side tool support and having a fixed pivotal connection, and an adjustable connection between said swinging and sliding tool supports whereby the tools carried thereby may simultaneously operate upon the work and successively upon the same piece of work.

23. In a multiple spindle machine, the combination of a rotatably supported turret carrying a plurality of spindles for the work, a pair of side tool supports movable toward and from the work, simultaneously, so that the tools carried by said tool supports may operate simultaneously upon the work and successively upon the same piece of work, and a tool carried by each of said tool supports, the cutting edge of one being at an angle to the line of movement while the cutting edge of the following tool is oppositely inclined, whereby the tools are adapted to make shearing cuts.

24. In a multiple spindle machine, the combination of a rotatably supported turret carrying a plurality of spindles for the work, a side tool support movable toward

and from the work, another side tool support located above said first side tool support and connected and movable therewith toward and from the work so that the tools carried by said tool supports may operate upon the work and successively upon the same piece of work, means for actuating said supports simultaneously, and tools carried by said tool supports each adapted to make a cut different from that of the preceding tool and whereby each will partly or irregularly cut the work so that the complete forming operation on each piece is effected in materially less time than when the work is formed by a single tool and with less vibration and chattering when operating upon irregular stock.

25. In a multiple spindle machine, the combination of a rotatably supported turret carrying a plurality of spindles for the work, a side tool support movable toward and from the work, another side tool support located above said first side tool support and connected and movable therewith toward and from the work so that the tools carried by said tool supports may simultaneously operate upon the work and successively upon the same piece of work, and tools carried by said tool supports, the cutting edge of one being at an angle to the line of movement while the cutting edge of the following tool is oppositely inclined, whereby each is adapted to make a shearing cut, and whereby each tool will partly or irregularly cut the work so that the complete forming operation on each piece of work is effected in materially less time than when the work is formed by a single tool and with less vibration and chattering when operating upon irregular stock.

26. In a multiple spindle machine, the combination of a rotatably supported turret carrying a plurality of spindles for the work, a pair of side tool supports movable toward and from the work, and connected together so that the tools carried by said tool supports may simultaneously operate upon the work and successively upon the same piece of work, said tool supports carrying tools, the cutting edge of one being at an angle to the line of movement while the cutting edge of the following tool is oppositely inclined.

27. In a multiple spindle machine, the combination of a rotatably supported turret carrying a plurality of spindles for the work, two pairs of side tool supports movable toward and from the work, so that the tools carried by said tool supports may simultaneously operate upon the work and successively upon the same piece of work, one pair of said tool supports carrying tools, the cutting edge of one being at an angle to the line of movement while the cutting edge of the following tool is oppositely

inclined, whereby each is adapted to make a shearing cut.

28. In a multiple spindle machine, the combination of a rotatably supported turret carrying a plurality of spindles for the work, a fixed bracket, an eccentrically formed shaft carried by the bracket, a swinging side tool support suspended from said shaft, a linkage connection between said shaft and the swinging side tool support and also having a fixed pivotal connection, and means for imparting a swinging movement to said swinging side tool support.

29. In a multiple spindle machine, the combination of a rotatably supported turret carrying a plurality of spindles for the work, a side tool support, means for eccentrically supporting it for swinging movement, and means for actuating said means and for swinging said tool support toward and from the work.

30. In a machine of the class described, the combination of a fixed bracket, an eccentrically supported shaft carried by the bracket, a swinging side tool support suspended from said shaft, a linkage connection between said shaft and the swinging side tool support and also having a fixed pivotal connection, and means for actuating said tool support.

31. In a multiple spindle machine, the combination of a rotatably supported turret carrying a plurality of spindles for the work, a fixed bracket supported adjacent to said turret, an eccentrically formed shaft carried by the bracket, a swinging side tool support suspended from said shaft, a linkage connection between said shaft and the swinging side tool support and also having a fixed pivotal connection, and means for actuating said tool support.

32. In a multiple spindle machine, the combination of a rotatably supported turret carrying a plurality of spindles for the work, a side tool support movable toward and from the work, an overhanging swinging side tool support, means for giving said swinging tool support a rising and falling movement during its swinging movement,

and means for actuating both of said tool supports.

33. In a multiple spindle machine, the combination of a rotatably supported turret carrying a plurality of spindles for the work, a side tool support movable toward and from the work, a swinging side tool support overhanging said first side tool support, means for giving said swinging side tool support a rising and falling movement during its swinging movement, and means for actuating both of said tool supports, each of said tool supports carrying a tool adapted to make a cut one in a direction opposite to that of the other.

34. In a machine of the class described, the combination of supporting means, a side tool support supported thereby for rising and falling movement and for swinging movement during its rising and falling movement, and mechanism for swinging said side tool support and for imparting a rising and falling movement during its swinging movement.

35. In a multiple spindle machine, the combination of a rotatably supported turret carrying a plurality of spindles for the work, two sets of side tool supports, each set comprising a pair of side tool supports, and means for actuating all of said supports in unison whereby the tools carried thereby may simultaneously operate upon the work and successively upon the same piece of work, three of said side tool supports carrying forming tools each constructed to partly or irregularly cut the work whereby the complete forming operation on each piece is effected only by all of the tools but in materially less time than when the work is formed by a single tool and with less vibration and chattering when operating upon irregular stock.

Signed at Cleveland, in the county of Cuyahoga and State of Ohio, this 21st day of February, 1912.

HUGH MUNROE HUNTER.
